UNITED STATES PATENT OFFICE.

ALVIN J. BASSETT, OF MILWAUKEE, WISCONSIN, ASSIGNOR TO SHARP-BASSETT GAS PRODUCER COMPANY, OF MILWAUKEE, WISCONSIN.

GAS-PRODUCER.

1,098,875.

Specification of Letters Patent.

Patented June 2, 1914.

Application filed September 29, 1913. Serial No. 792,512.

To all whom it may concern:

Be it known that I, ALVIN J. BASSETT, a citizen of the United States, and resident of Milwaukee, in the county of Milwaukee and State of Wisconsin, have invented certain new and useful Improvements in Gas-Producers; and I do hereby declare that the following is a full, clear, and exact description thereof.

10 The general object of my invention is to provide a simple, economical and effective gas producer, it being especially applicable to that type of producer for which a patent was granted to William F. Luick and myself May 27, 1913, No. 1062721.

Specific objects of my invention are to provide a water-jacketed gas-receiving throat in connection with the head of a gas producer fire-pot, the said throat being extended into the pot, whereby the generated gases are collected and discharged through a suitable pipe connection to said throat, the throat being thus protected from burning out through its water-jacket connections.

20 By this arrangement of gas-receiving throat a further advantage lies in the fact that the ascending gas is more or less pocketed above the mouth of the throat between the head and fire-pot walls and is thereafter caused 25 to descend and enter said throat from all sides in an even flow.

Another object of my invention is to provide an inclosed air chamber about the fire-pot provided with means for supplying steam thereto, whereby the air is humidified to a desired degree, the humidified air from the chamber being discharged under the fire-pot for effecting combustion by means of a conducting pipe.

30 A further object of my invention is to provide a humidistat in connection with a conducting pipe, the said humidistat being adapted to control a valve for supplying steam in varying quantities to the air, such 35 supply being regulated automatically.

With the above objects in view the invention consists in certain peculiarities of construction and combination of parts as hereinafter set forth with reference to the 40 accompanying drawing and subsequently claimed.

The drawing illustrates a central sectional elevation of a gas producer embodying the features of my invention.

45 Referring by characters to the drawing,

1 represents an incasing jacket provided with a head having upper and lower spaced plates 2, 2', which plates are connected at their circular edges by a band 2", whereby a hollow head or water-chamber is formed, the water-chamber being supplied by means of a pipe connection 3. The head has also connected thereto a valve-controlled magazine 4, whereby fuel is admitted to the producer, the said water-chamber being also provided with a water-pipe connection 3', which connection is disposed at the water-line. The lower plate 2' of the water-jacketed head is centrally apertured for the reception of a double walled gas-receiving throat 5, which throat extends downwardly and is flanged for the reception of bolts, whereby it is secured to said plate, the space between its walls being in communication with the water-chamber of the head. Secured to the flanged end of the gas-receiving throat in a gas-delivery pipe 6, which pipe is formed with an elbow and is also provided with a cap-closed poke-hole 6'.

Extending about the incasing jacket and spaced therefrom is a metallic shell 7, the upper end of which shell is secured to the lower plate 2' of the head, the space between said shell and jacket constituting a chamber that is sub-divided into compartments, admission of air to the upper one of same being effected through an air intake nipple 8, which is suitably threaded for the reception of a supply-pipe, not shown. The lower end of the shell 7 is flanged outwardly and connected to the incasing jacket 1 intermediate of the length of said casing jacket, to thus close the chamber at this point. The chamber is also provided with an apertured ring 8' just below the air intake nipple forming an air receiving compartment *a* and a corresponding apertured ring 8" at a predetermined distance from the bottom of the air chamber, the space between said rings constituting an air mixing compartment *b*. Hence it will be seen that the chamber formed in connection with the shell 7 and jacket is sub-divided into three compartments comprising an upper air-receiving compartment *a*, an intermediate mixing compartment *b*, and a lower air storage compartment *c*. The fluid-supply pipe 3' which extends from the producer head is provided with a branch-pipe 9, which pipe communicates with the mixing 100

compartment of the air chamber and is provided with a controlling valve 9' having an actuating lever 9", it being understood that the fluid supply pipe 3' extends to a 5 scrubber mechanism, not shown. Directly under the mouth of the fluid-pipe 9 a V-shaped drip-pan 10 is provided, in the form of a ring, the same being secured, as shown, to the jacket 7, whereby condensation of 10 steam from the mouth of said pipe is trapped, there being sufficient space between the outer edge of the drip-pan and jacket 1 to permit free passage of air. The shell 7 has fitted thereto the usual fire-brick walls 15 11 of a circular fuel pot, which walls extend to the lower plate 2' of the head and terminate slightly below the air chamber, at which point they are supported by a ring 11', the same being, in turn, supported by 20 brackets 12 that are secured to the jacket 1. The ring 11' also carries an inwardly flared metallic fire-pot hopper 13, which is preferably formed in detachable sections and under this fire-pot is arranged a suitable 25 rocking grate 14, the same being disposed in the ash-pit section of the jacket, which ash-pit section extends from the ring 11 to the bottom of said jacket.

The mouth of a conductor pipe 15 is arranged to communicate with the air storage compartment *c* of the chamber, which pipe is in the form of an elbow having a horizontal section 15' that extends into the ash-pit, terminating with an upwardly discharging mouth in axial alinement with the fuel-pot and directly under the grate. Extending within the vertical leg 15 of the conductor pipe is a humidistat 16 provided with a lever mechanism 16', which mechanism is connected to the actuating lever 9" of the steam supply valve 9' by a rod 17, whereby the valve 9' is controlled through the action of said humidistat.

In the operation it is obvious that air 45 forced through the nipple 8, will pass through the apertures of the first ring 8' and be slightly retarded prior to being discharged below the second ring 8". Incidental to the air being momentarily retarded 50 within the mixing compartment, water is admitted thereto, whereby the air will absorb the proper degree of humidity to effect perfect combustion. The humidified air is thereafter caused to travel through the conductor pipe and be discharged under the fuel pot. Should the humidity increase over a predetermined degree, the humidistat 55 will act upon its lever mechanism 16' and thus cut off or restrict the supply of water by means of its valve connection to the water pipe or vice versa.

It is obvious that, owing to the fact that the gas-receiving throat projects downwardly and centrally of the fuel pot, it will 60 cause a large percentage of the gas to be

pocketed at the head end of the pot, which gas must return and be discharged in an even flow into the mouth of the throat, whereby it is collected and then delivered to the point of storage or consumption and, 70 furthermore, that, owing to the fact that the water jacketed head of the producer being in communication with a chamber formed between the double walls of the receiving throat, the same is held at a sufficiently low temperature to prevent burning out and, furthermore, this increased area of the water jacket also serves to correspondingly increase the capacity of said jacket as a water heater for supplying the humidifier. 75

Particular attention is called to the fact that the chamber about the casing is divided by the perforated rings 8', 8", first into an upper compartment for receiving the supply of air the volume of which is retarded or choked in its flow to the mixing compartment *b* therebelow as it flows through the ring apertures. Hence the slightly confined air in the upper compartment will be distributed equally about the casing and be discharged in a uniform sheet to the mixing compartment therebelow where it receives the humidifying fluid. The humidified air in the mixing compartment is then slightly retarded to permit perfect humidification 90 and thereafter the evenly humidified air is then discharged through the apertures in the lower ring 8' into the storage compartment *c*, from which storage compartment it is drawn off and delivered under the grate. 95 This method of interrupting the air and successively causing it to travel from one compartment to the other materially increases the efficiency of the apparatus and insures a uniform mixture of properly humidified air being supplied to the grate for producing combustion, thus eliminating all tendency of air being discharged only partially treated. 100

I claim:

1. In a gas producer having a jacket, a head closure therefor, and an interior shell in connection with the jacket to form a chamber closed at its ends; the combination of perforated upper and lower rings extending around the air chamber and spaced from its respective closed ends to form an upper air-receiving compartment, a mixing compartment and a lower storage compartment, means for admitting air to the upper air-receiving compartment, means for admitting fluid to the air mixing compartment whereby said air is humidified, and a pipe connection in communication with the lower air storage compartment, the said pipe being 115 terminated with a discharge mouth under the fuel pot. 120

2. In a gas producer having a jacket, a head closure therefor, and an interior shell in connection with the jacket to form a 130

chamber closed at its ends; the combination of perforated upper and lower rings extending around the air chamber and spaced from its respective closed ends to form an upper
5 air-receiving compartment, a mixing compartment and a lower storage compartment, means for admitting air to the upper air-receiving compartment, an evaporating pan mounted in the mixing compartment, means
10 for discharging fluid into the evaporating pan whereby air contained in the mixing compartment is uniformly humidified, and a

pipe connection in communication with the lower air storage compartment, the said pipe being terminated with a discharge mouth 15 under the fuel pot.

In testimony that I claim the foregoing I have hereunto set my hand at Milwaukee in the county of Milwaukee and State of Wisconsin in the presence of two witnesses.
